ATTORNEY

UNITED STATES PATENT OFFICE

ALFRED ORDE TATE, OF TORONTO, ONTARIO, CANADA

CIRCLE SEGMENTATOR

Application filed November 7, 1928. Serial No. 317,838.

This invention relates to an instrument or device for guiding a tool or marker in making or engraving arcuate or circumferential and radial markings or lines on a plate or disc, as described in the present specification and illustrated in the accompanying drawings which form part of same.

The invention consists essentially of the novel features pointed out broadly and specifically in the claims for novelty following a description containing an explanation in detail of an acceptable form of the invention.

The objects of the invention are to reduce the time and labour required in making circumferential and radial lines or markings on a plate or disc; to facilitate the location of a certain point in regard to a common centre; to allow for the finest adjustment of the marker with regard to a certain point on the surface of a plate or planed surface without difficulty or undue eye strain; to aid in the reproduction of the markings on different plates or planed surfaces with a minimum of variation; to so construct such a device that it may carry either a marker or pencil or an engraving tool or the like; and generally, to provide a device rugged in construction, simple in form, and capable of accomplishing the aforesaid results and purposes.

I may further state that the necessity for an instrument embodying these functions was indicated to me by my work in marking or engraving discs with radial and circumferential lines to define the boundaries of the radial and circumferential spaces or areas which are subsequently opened up to effect visualization through the said discs when they are prepared and revolved as described in my application for United States Letters Patent Serial No. 311,118, filed October 8, 1928, for apparatus for treating light and similar rays.

In the drawings, Figure 1 is a plan view of the device complete.

Figure 2 is an end elevational view showing the angular adjustment.

Figure 3 is a fragmentary section view taken on lines 3—3 in Figure 1.

Figure 4 is a fragmentary plan view showing the different adjustments.

Figure 5 is a fragmentary section view taken on lines 5—5 in Figure 3.

Figure 6 is a fragmentary section view showing a tool mounted for engraving.

Like numerals of reference indicate corresponding parts in the various figures.

Referring to the drawings, the numeral 10 indicates the device complete mounted on a table or platform 11. The platform 11 consists essentially of a planed top, preferably a rigid metal plate 12 suitably supported on a framework or base 13. The instrument consists essentially of a plate 15 pivotally mounted at its central axis on a bearing disc 16 rigid with the plate 12 and at the central axis thereof and an arm 17 rigid with the portion 15 and extending therefrom a distance and being of the same cross section throughout its length, and a pencil or marker 18 reciprocally carried on the bar 17. The bar 17 is offset from and parallel with a radial line passing through the central axis or the pivotal point of the plate 15 as indicated at B in Figure 4, so that the point of the pencil or marker 18 which is carried on a ferrule or sleeve 19 reciprocally mounted on the bar 17 will fall directly on said radial line when said ferrule is reciprocated on the bar 17.

The bar 17 is so mounted that it will be adjacent to and substantially parallel with the surface of the plate 12. In order to do this, it is preferably slightly offset from the plate 15 to which it is secured as at 17a. The plate 15 is rotatably mounted on the pivotal bearing 16 and secured in position by a suitable bolt or cap screw 15b at the central axis and is so mounted that there will be a minimum of side play when the bar 17 is pivoted about the central axis of the pivoting point. In order to reduce to a minimum any thrust or looseness in the pivotal mounting of the plate 15 on the bearing 16, a raised ring 15a is formed on the under side of the plate 15 adapted to snugly fit in a circular groove 16a formed on the upper surface of the bearing plate 16.

The numeral 24 indicates any plate or disc on which the markings or engravings are to

be placed. An opening 25 is formed there-through and at the axis about which the markings are to be placed. The plate 24 rests on the plate 12 and the pivotal bearing block 16 rests on said plate 24 and at said axis. A threaded extension 20 is formed on the under side of the pivotal bearing block 16 and is adapted to pass through the opening 25 in the plate 24 and an opening 21 formed in the plate 12. The extension 20 forms a snug fit in the openings 25 and 21. A nut 23 is threaded onto the extension 20 and bears against the underside of the plate 12 in order to rigidly secure the plate 24 and the pivotal bearing block 16 in position.

The ferrule 19 carrying the pencil or marker 18 is mounted on the bar 17 so that it may be reciprocated on said bar and must form a snug fit with same so that there will be no play or looseness in its mounting thereon. The pencil or marker 18 is so mounted on the ferrule 19 that it will be substantially vertical in regard to the surface of the plate 24. The marker 18 is preferably reciprocally and resiliently mounted in the ferrule 19 so that an even pressure will be exerted by the point of the marker on the surface of the plate 24. In order to so mount the pencil or marker 18 on the ferrule 19, a recessed portion 26 is formed on the underside of said ferrule and an opening 27 is formed from the upper side of the ferrule into said recessed portion. The pencil or marker 18 is reciprocally mounted in the opening 27. A compression spring 28 impinging against the end wall of the recess 26 and against a pin or shoulder 29 formed adjacent to the lower end of the marker 18 tends to retain said marker in contact with the surface of the plate 24. In order to prevent looseness or a side thrust of the marker in its mounting in the ferrule 19, a ring 30 having a centrally located opening 31 forming a snug working fit with the lower end of the marker 18 may be threaded as at 32 into the lower portion of the recess 26. A lug or projection 33 is formed on the upper surface of the ferrule 19 and is adapted to engage on lifting the marker 18 and rotating same a partial turn, a pin or projection 34 formed adjacent the upper end of said marker to effectively retain same out of engagement with the surface of the plate 24. A knob 35 may be formed on or secured to the upper end of the pencil 18 for better gripping the pencil to adjust it.

In order to fix the bar 17 in any angular position in regard to a radial line from the central axis of the plate 24, a plurality of indentations or openings 36 are formed in the plate 11 at regular intervals and equidistant from said central axis and are adapted to be engaged by a pin 37 carried adjacent the end of said bar 17. The number of openings 36 is preferably 360 or a multiple thereof, corresponding to the number of degrees in a circle.

The openings are graduated as at 38 from zero point, similarly to the markings on a protractor, to denote the number of degrees in the angle between the zero point and the particular opening into which the pin 37 may be inserted to lock the bar 17 in its corresponding position. If it is desired to provide a fine adjustment so that the bar 17 may be secured at a half or quarter degree point, the pin 37 may be reciprocally carried in a block 40 mounted adjacent the end of the bar 17 and adapted to be reciprocated at right angles to the longitudinal axis of said bar 17. A screw 41 is rotatably mounted in fixed bearing blocks 42 and threaded through the block 40 and has its longitudinal axis parallel to the path of reciprocation of said block 40. A graduated knob or dial 43 is fixed to one end of the screw 41 to indicate the distance travelled by the block 40 on the rotation of the screw 41.

In order to provide a fine radial adjustment for the ferrule 19 on the bar 17 when it is desired to place the marker and retain same at the proper distance from the central axis, a screw adjustment may be provided. The bar 17 is graduated as at 46 to denote the relative position of the marker 18 in regard to the central axis.

A screw 47 parallel with the bar 17 and rotatably mounted at one end as at 48 in the plate 15 and at the other in the block 49 detachably secured to the end of the bar 17 by the bolts or screws 50, is threaded into a nut 51 adapted to detachably engage a slot or groove 52 formed in the ferrule or sleeve 19 so that said ferrule will be reciprocated on the bar 17 on the rotation of said screw 47. A graduated dial 53 is rigidly secured to the end of the screw 47 to indicate the rotation of said screw and the distance through which the ferrule has been reciprocated.

This device is particularly adapted for forming circumferential and radial markings in regard to a fixed centre. In the operation thereof, the pivotal block 16 is mounted at the central axis about which the markings are to be placed in the manner as described heretofore. When it is desired to mark radial lines or boundaries only, the screw adjustment governing the reciprocation of the ferrule 19 on the bar 17 is detached from said bar 17 by the removal of the screws or bolts 50 and removing the nut 51 from the groove 52. The ferrule may be now freely reciprocated on the bar 17 and by disengaging the extension 34 from the raised portion 33, the pencil or marker is brought into contact with the surface to be marked of the plate 24. The pin 37 is now placed in the proper opening 36 for securing the bar 17 in the required position for forming the particular radial line at that angle. If it is desired to set the bar 17 at a point midway between two degree points, as indicated by

the openings 36, the screw 41 is rotated the proper distance as indicated on the dial 43. The radial lines or markings may now be formed by reciprocating the ferrule 19 along the bar 17 the proper distance, according to the length of the line to be made.

When it is desired to form circumferential markings or arcs in regard to a central axis, the nut 51 is placed in the groove 52 and the block 49 is secured to the bar 17 by the screws or bolts 50. The ferrule is brought to the proper position in regard to the radius of the circumferential arc or circle to be formed by rotating the screw 47. The pin 37 is lifted so that it will be disengaged from the openings 36 and the bar 17 carrying the ferrule 19 and the marker 18 may be pivoted about the central axis to form the proper circle or arc.

In Figure 6 is shown how a routing or engraving tool may be mounted in the ferrule 19 in place of the pencil or marker 18. The numeral 60 indicates the routing tool. The shaft 61 of the tool 60 may be journaled in the opening 27 and also adjacent to its lower end in the washer 63 reciprocally mounted in the recess 26. The washer 63 bears against a shoulder 64 formed on the shaft 61. The spring 28 impinges against the upper surface of the washer 63 and thus promotes an even pressure of the tool 60 onto the surface 24 to be engraved. In order to disengage the tool 60 from the surface 24, a nut 65 is rotatably mounted at the upper end 35 of the shaft 61 and bears as at 67 against the collar 66 secured on the shaft 61. A lug 68 is formed on one side of the nut 65 and is adapted to engage the shoulder or lug 33 on rotating said nut to the proper position, to effectively retain the tool out of contact 40 with the surface 24.

What I claim is:

1. A device for guiding a scribe, a platform for same having a planed upper surface, there being a plurality of recesses formed in said upper surface and at regular intervals and equidistant from the central axis of said upper surface, a bar pivotally mounted at one end at said central axis and offset from and parallel to a radial line drawn from said central axis and adapted to be pivoted about said axis in a plane parallel to the surface of said platform, a ferrule reciprocally mounted on said bar and adapted to carry the scribe and so position same that the point of said scribe will fall on said radial line, means for releasably locking said ferrule at any required distance from the central axis, and a projection carried adjacent the end of said bar adapted to engage any of the recesses to releasably lock said bar in any position in the plane in which it is pivoted.

2. A device for guiding a scribe, a platform for same having a planed upper sur-

face, there being a plurality of recesses formed in said upper surface at regular intervals and equidistant from the central axis of said upper surface, a bar pivotally mounted at one end at said central axis, a ferrule 70 reciprocally mounted on said bar and forming means for carrying the scribe in such a manner that when said ferrule is reciprocated on said bar, the point of the scribe will fall along a radial line from said pivoting point or central axis, means for releasably locking said ferrule to said bar at any required distance from said central axis, a block mounted on said bar adjacent the end, a pin mounted in said block and adapted to engage said recesses, and means for varying the relative position of said block with respect to said bar along a line normal to a radial line from said central axis.

3. A device for guiding a scribe for marking arcuate lines on a planed surface of a disc, a platform to support said disc, a block bearing on said disc and secured to said platform at the central axis thereof, a bar pivotally mounted on said block and adapted to pivot about its mounting in a plane parallel to the surface of said platform, a ferrule reciprocally mounted on said bar and adapted to carry said scribe in such a manner that the point thereof will fall on a radial line passing through said pivoting point, a block reciprocally mounted on said bar and adjacent the end thereof and adapted to reciprocate in a direction normal to a radial line through said pivoting point and in a plane 95 parallel to said platform, a screw through said block and adapted on rotation to reciprocate said block in its mounting, a pin on said block adapted to engage openings in said platform to releasably lock said bar in any position in the plane in which it pivots, and means for releasably locking said ferrule on said bar at the desired distance from said central axis.

4. A device for guiding a scribe for making radial lines on a planed surface, a platform adapted to support a sheet, disc, or the like on which said markings are to be placed, a block adapted to engage and lock said platform and said plate at the central axis, a bar pivotally mounted on said block at the central axis of said platform and in a plane parallel to said platform, a ferrule reciprocally mounted on said bar adapted to carry the scribe in such a manner that the point thereof will fall in a radial line through said central axis, a screw parallel with said radial line to said central axis and adapted to be rotatably mounted on said bar, a gripping member rigidly secured to said screw and having suitable graduation marks, a nut threaded onto said screw and adapted to releasably engage said ferrule, means for releasably mounting said screw on said bar, and a pin carried by said bar adjacent the end distant 130

from the pivoting block of said bar, said pin being adapted to releasably engage indentations in said platform spaced at regular intervals and equidistant from the central axis thereof.

5. In a device for guiding a scribe for making radial or circumferential markings on a planed surface, a platform adapted to support a work sheet on which said markings are to be placed, a block adapted to be secured to said platform and to engage said sheet at its central axis to retain same in fixed relation with said platform and said block, a bar pivotally and radially mounted on said block, a pencil carrier reciprocally mounted on said bar, means for releasably locking said carrier at any place along said bar, means for releasably locking said bar at select points about its pivotal block, and means including a vernier adjustment for pivoting said bar a slight distance independently of locking means.

Signed at the city of Toronto, this 29th day of October, 1928.
